ELECTRICAL CONNECTOR

Arthur W. Faires, Leland E. Fine, and William H. Green, Wilkes-Barre, Pa.; Martha Faires administratrix of Arthur W. Faires, deceased; said administratrix assignor to Martha Faires, Wilkes-Barre, Pa.

Application March 30, 1938, Serial No. 198,998

5 Claims. (Cl. 24—81)

This invention relates to electrical connectors and, in its more specific aspects, to safety clamps for connecting and disconnecting a "hot" or high tension line wire to an insulator.

5 According to current practice, high tension line wires are connected to an insulator by a tie which consists of a length of wire usually running from about 54" to 74" in length. This tie wire is passed around the insulator head and 10 then wrapped around the line wire to secure the latter to the insulator. The task of applying tie wires as aforesaid is a difficult as well as a hazardous undertaking, with the lineman effecting the tie by the use of so-called "hot line sticks".

15 When, in the case of line trouble or replacement of an insulator, it becomes necessary to untie the line wire from the insulator, the unwrapping of the tie wire is a laborious and time-consuming proceeding and, by reason of the likelihood of the loose end of the tie wire coming in contact with a parallel line wire, there exists great danger of short-circuiting the line under repair. The use of tie wires is further disadvantageous in that they loosen with the sway 20 and vibration of the line, causing an arc which is believed to result in radio interference.

While there have been hitherto made suggestions of mechanical clamps for securing line wires to insulators, such have not been successful 30 or practical, with the result that the use of tie wires has prevailed, despite the recognized disadvantages and danger to the lineman inherent in their use, as well as high labor costs involved in applying the tie wire and in removing it when 35 repair of the line wire or insulator is necessary.

Accordingly, among the objects of the present invention may be noted the provision of improved means of securing a line wire to an insulator 40 which does away with tie wires, which may be applied with a minimum of labor, and which may be applied and thereafter operated with minimum hazard to the lineman; the provision of a mechanical clamp for securing a line wire 45 to an insulator, which is simple and inexpensive in manufacture, which may be applied with facility to the insulator, and which is efficient and durable in use and operation; the provision of a clamp for line wires, which is characterized by a 50 high degree of safety in application and subsequent operation; the provision of a clamp for line wires which may be readily applied to the insulator, either before or after mounting of the insulator on the pole cross arm, and which may 55 be mechanically operated both to secure the line

wire to the insulator and to uncouple the line wire from the insulator as may be required.

Other objects will be in part obvious and in part hereinafter pointed out in connection with the following analysis of this invention wherein is illustrated an embodiment of the invention in detail.

In the drawing—

Fig. 1 is a part section view of a line wire clamp in accordance with the present invention, applied 10 to a pin type insulator and securing a line wire thereto;

Fig. 2 is a top plan view of the clamp as illustrated in Fig. 1;

Fig. 3 is a section taken along lines 3—3 of 15 Fig. 1; and

Fig. 4 is a separated view of a clamp with securing means therefor such as is suitable for securing the clamp to an insulator of a double cross arm construction. 20

In the drawing, wherein like reference characters designate like parts throughout the several views, the reference character 10 designates an insulator which may be of the pin type for mounting on pins projecting upwardly from a 25 pole cross arm (not shown), the insulator having a head portion 11 provided with a longitudinal line wire receiving groove 12 and a neck portion 13 of reduced diameter, the latter being more clearly shown in Fig. 2. With a single cross arm 30 it is desirable that the line wire be secured at both sides of the insulator 10, and to this end companion clamp elements as illustrated in Figs. 1, 2 and 3 are provided. Each of said clamp elements includes an elongated base plate 15, from 35 one end of which extends, preferably in integral manner, a semi-circular strap 16 adapted to be secured to a reversely disposed semi-circular strap 17 of the companion clamp. As will be observed from Fig. 2, the straps 16, 17 of the 40 companion clamps are secured to each other about the neck portion 13 of the insulator, through securing bolts 18, 19, whereby the companion clamp elements are fixedly secured to the insulator. 45

Extending through an unthreaded hole in the base plate 15 of each clamp, which hole is disposed laterally of the longitudinal center line thereof, is a J-shaped clamp bolt 20, to the head of which is rigidly secured a grooved clamp jaw 21, the groove of which is adapted to overlie a longitudinal groove or depression 22 punched or otherwise formed in the base plate 15 and extending along the longitudinal center line of the base plate. 50 55

The arm of the clamp bolt 20 is reduced in diameter adjacent its end portion as indicated at 25 (Fig. 3), such reduced end, when the bolt is moved to its lowermost or wire clamping portion, 5 being received in a countersunk hole 26 in the base plate, thereby to prevent angling of the bolt as it is actuated into its final clamping position with reference to the base plate 15.

The shank portion of the bolt 20 is threaded, 10 but may move freely through the base plate 15. Actuating means for causing relative raising and lowering movement of the bolt is provided, such comprising a nut generally designated 28 (Fig. 3), the nut being seated in a socket formed on the 15 under face of the base plate by downstruck tongues 30, 31, the latter being bent inwardly to engage beneath shoulder 32 formed on nut 28. The socket-forming tongues 30, 31 provides a seat on which the nut 28 may be rotated, while 20 locating the nut so that it may be operated from below the base plate. The nut 28 is provided with a threaded axial bore which engages with the threaded shank portion of the bolt 20, and its lower end 23 is formed angular in section (preferably square) to provide a head for reception in the socket end 34 of a pole wrench 35 as indicated in Fig. 4.

The end of the base plate removed from the 30 securing strip is turned upwardly to provide a raised block portion 40 which is provided with a groove or depression 41 in alignment with groove 22 of the base plate, and with the wire receiving groove of the insulator head 11. By reason of the relative elevation of the block portion 40, with 35 reference to the base plate 15, groove 41 is disposed at or about the elevation of the head groove 12, with groove 22 of the plate having a lesser elevation.

As will be observed from Figs. 1 and 2, the 40 companion clamp elements are secured in aligned, fore and aft relation to the insulator 10 by nuts 18, 19 operating to secure the straps 16, 17 in encircling relation about the neck 13 of the insulator. Assuming that the line wire designated 45 45 is held by suitable means above the clamps, the jaws 21 are each turned so that its wire groove overlies the line-wire, and thereupon the jaw is lowered sufficiently until the head portion of the clamp bolt 20 is hooked over it. The clamp 50 bolt is thereupon lowered to its clamping position, this lowering movement being effected by bringing the socket end 34 of the pole wrench 35 into engagement with the square head 33 of the nut 28, the handle of the wrench being provided 55 with a bore 36 of sufficient length as to receive the shank portion of the bolt 20, as indicated in Fig. 1. Turning movement of the wrench handle 35 in proper direction causes rotation of the nut 28 in such direction as to move the bolt 20 downwardly. With the jaw 21 of the bolt disposed 60 over the wire 45, the wire is gripped with increasing force until it is finally clamped between the jaw 21 and the base plate 15, being disposed 65 in the grooves 22 and 41 of the base plate 15 and saddle block 40, respectively. Thus, simple rotation of the pole wrench 35 from below the clamp operates to securely clamp and also to tension the wire between the insulator head and the 70 tension block 40 due to the fact that the head groove 12 and the block groove 41 are at a greater elevation than the clamping surface of the base plate.

By the provision of companion clamps, as indicated in Figs. 1 and 2, the line wire is clamped

at both sides of the insulator and seats under tension in the head groove 12 of the insulator.

Where insulators are carried on spaced cross-arms mounted on both sides of the line carrying pole, such being the so-called double cross-arm construction, insufficient space is provided between the cross-arms as to permit the securing of companion clamps on each insulator, as with the single cross-arm construction. Accordingly, with the double cross-arm construction, one 10 clamp is used with each insulator of a cross-arm and is secured to the insulator neck by means of a semi-circular strap 16a cooperating with the strap 16 extending from base plate 15, as indicated in Fig. 4.

The ease with which clamps in accordance with the invention may be applied to insulators and the line wire thereupon connected in fixed manner both to the insulator and to the clamps will be apparent from the above description. If, 20 due to line trouble, or the requirement of replacing a broken insulator, it becomes necessary to disconnect the line wire from the insulator, such may be effected readily by coupling the pole wrench with the nut head 33 and turning the nut 28 in opposition direction than that already described. Such turning movement of the nut results in raising movement of the bolt 20 and clamp jaw 21, whereby to disconnect the wire from the 30 clamp and insulator, suitable means, such as a gin pole and block and tackle operated from the ground, being provided to raise the wire from the insulator to a safe working position with reference thereto. Upon correction of the line failure or replacement of the insulator, the line may 35 thereafter be lowered and clamped in the manner described.

It will be observed that clamps of the above character overcome the known disadvantages incident to the use of tie wires for tying line wires 40 to insulators and are further relatively safe in operation by reason of the fact that the clamps may be operated by a relatively long pole wrench, thus to overcome the requirement of the lineman working in proximity to the live wire.

The clamp as described further substantially eliminates the danger of short-circuiting the wire being worked on with a parallel wire, while at the same time reduces very materially the time necessary to secure or uncouple a line wire from 50 an insulator.

As many changes could be made in carrying out the above constructions without departing from the scope of the invention, it is intended that all matter contained in the above description or 55 shown in the accompanying drawing shall be interpreted as illustrative and not in a limiting sense.

We claim:

1. A safety hot-line clamp comprising, in combination, an elongated base member, means on one end of the member for securing the latter to an insulator, a J-shaped clamp bolt whose head provides a clamp jaw and having a threaded shank extending through the base member, and 65 a rotatable nut threadedly related to the shank portion and operatively secured to the base member, said nut being operative from beneath the base member to actuate the bolt through said member whereby to move the jaw toward and 70 away from the upper face of the member.

2. A safety hot-line clamp comprising, in combination, an elongated base member, means at one end of the member for securing the latter to an insulator, a J-shaped clamp bolt whose head pro- 75

vides a clamp jaw and having a threaded shank extending through the base member, a rotatable nut threadedly related to the shank portion, means on the under face of the base member forming a socket for the nut, the nut being operative from beneath the member to actuate the bolt therethrough, whereby to move the clamp jaw toward and away from the upper face of the member.

- 10 3. A safety hot-line clamp comprising, in combination, an elongated base member, means on one end of the member for securing the latter to an insulator, a clamp bolt having a substantially J-shaped head, a clamp jaw carried by the head, the bolt having a threaded shank extending through the base member, a nut socket on the under face of the base member, a nut threaded on the shank portion and carried by said nut socket, the nut being operative upon rotation to actuate the bolt through the base member, said member having an opening in its upper face and the bolt head having a portion engageable in said opening upon movement of the bolt to its lowermost position with reference to the base member.
- 25 4. A safety hot-line clamp comprising, in combination, an elongated base member having a substantially horizontal upper face, means at one end of the base member for securing the same to an insulator, a bolt member having a threaded shank portion which extends through and below the base member, a jaw member carried by the bolt at the upper end thereof, the bolt being arranged both for turning and axial movement whereby the jaw member may be turned to and away from a position in which it may engage over

a line wire to be clamped and whereby the jaw member may be moved towards and away from the base member, a rotatable nut having threaded engagement with the shank portion of the bolt, and means on the under face of the base member 5 for securing the nut thereto while permitting free rotation thereof with reference to the base member.

5. A safety hot-line clamp comprising, in combination, an elongated base member having a substantially horizontal upper face, means at one end of the base member for securing the same to an insulator, the base member having an unthreaded hole therethrough disposed laterally of the longitudinal center line of the base member, 15 a bolt member having a threaded shank portion passing through said hole and terminating below the base member, a jaw member carried by the bolt at the upper end thereof and having a wire receiving groove, the bolt being arranged both 20 for turning and for axial movement whereby the jaw member may be turned to and away from a position in which it may engage over a line wire with its wire receiving groove extending along the longitudinal center line of the base member 25 and whereby the jaw member may be moved toward and away from the base member, a rotatable nut having threaded engagement with the shank portion of the bolt, and means on the under face of the base member for securing the nut 30 thereto while permitting free rotation thereof with reference to the base member.
